UNITED STATES PATENT OFFICE.

ROBERT R. BUSH AND CHARLES W. DAKE, OF CHICAGO, ILLINOIS, ASSIGNEES TO PYLE-NATIONAL COMPANY, OF CHICAGO, ILLINOIS, A CORPORATION OF NEW JERSEY.

DUPLEX NOZZLE FOR LOCOMOTIVES.

Application filed October 6, 1926. Serial No. 139,952.

Our invention relates to an improvement in nozzles for locomotives and has particular reference to a duplex or multiple nozzle. One object is the provision of a nozzle for controlling the discharge of the locomotive exhaust pipe. Another object is the provision of a duplex or multiple nozzle whereby, selectively, a plurality of nozzles of different sizes may be aligned with the discharge end 10 of the locomotive exhaust pipe. Another object is the provision of such a multiple nozzle which is easily controlled and which is preferably controllable from the exterior of the locomotive. Other objects will appear from time to time in the course of the specification and claims.

We illustrate our invention more or less diagrammatically in the accompanying drawings, wherein—

20 Figure 1 is a section through the forward portion of a locomotive, with parts in elevation;

Figure 2 is a front elevation of the locomotive;

25 Figure 3 is a vertical transverse section through the structure shown in Figure 2;

Figure 4 is a vertical section on an enlarged scale through the end portion of the exhaust pipe or stand;

30 Figure 5 is a section on the line 5—5 of Figure 4;

Figure 6 is a section similar to Figure 5 with the duplex nozzle in the alternative position;

35 Figure 7 is a detail section illustrating the external control; and

Figure 8 is a plan view of the structure shown in Figures 4, 5 and 6.

Like parts are illustrated by like symbols

40 throughout the specification and claims.

A generally indicates the wall of the locomotive housing and A¹ the forward closure thereof.

B is the exhaust pipe of the locomotive, 45 namely the steam pipe through which is delivered the exhaust from the cylinders. B¹ is any suitable terminal pipe section or stand, provided with the flange B² whereby it is secured to the end of the pipe B by means of the

bolts B³. The member B¹ is provided with 50 diametrically opposed outwardly projecting lugs B⁴ apertured as at B⁵. B⁶ indicate stops or lugs outwardly projecting from the upper portion of the member B¹ and each provided with the inclined lower surfaces B⁷ and B⁸. 55

C C¹ are webs or segments associated with which and preferably but not necessarily integral with which are the nozzle members C² and C³. The webs are provided with hub members C⁴ C⁵ centrally apertured as at C⁶ 60 C⁷.

Passing through the aperture C⁶ is the trunnion member C⁸ which is secured to C⁴ for example by means of the nuts C⁹ and bolts C¹⁰. Similarly secured to the member C⁵ is the plate C¹¹ with the apertured boss 65 C¹², through which passes the shaft D the end of which is adapted to serve as a trunnion penetrating one of the apertures B⁵. C¹⁴ indicates a pin whereby relative movement of the shaft D and the plate C¹¹ is prevented. 70

C²⁰ C²¹ are lugs on the webs C, C¹ opposed to the surfaces B⁷ B⁸ of the lugs B⁶. The shaft D extends forwardly through the forward wall A¹ of the locomotive housing and through the sleeve D¹ secured to the exterior 75 thereof. D² is any suitable packing therein contained, held for example by the screw threaded packing member D³. D⁴ is any suitable lever at the end of the shaft D which is associated with any suitable stop or travel limiting member D⁵, preferably formed with terminal holding notches D⁶, D⁷, into which the lever may be sprung.

E is any suitable apron or enclosure structure into which the exhaust pipe B¹ is adapted to discharge, E¹ is the smoke stack of the locomotive and E² any suitable interior petticoat pipe therefor.

The upper face of the exhaust pipe section B¹ is shaped in the arc of a circle struck about the center of the shaft D and trunnion C⁸ as shown at B⁹. The lower face of the nozzle members C², C³ are correspondingly shaped as at C¹⁵ to form close contact with the face B¹⁰. 90

95 It will be realized that whereas we have described and shown a practical and operative device nevertheless many changes might

be made in the size, shape, number and disposition of parts without departing from the spirit and we therefore wish our drawings to be taken as in a broad sense illustrative and diagrammatic rather than as limiting us to our specific showing.

The use and operation of our invention are as follows:

In employing the exhaust steam of a locomotive for maintaining or controlling the draft of the locomotive it frequently happens that conditions so vary that it is desirable to control the discharge of the exhaust. We have therefore provided a duplex nozzle member by the employment of which we may increase or diminish the velocity of the steam or vapor discharged from the exhaust pipe. We illustrate a duplex nozzle but it will be obvious that under some conditions a choice of more than two nozzles may be necessary and we wish it to be understood that our invention is not limited to the employment of two nozzles only.

In order to permit the quick and easy adjustment of the nozzles we have provided the control shaft D with its external control lever D⁴, whereby the engineer or fireman may almost instantaneously vary the exhaust discharge by substituting one nozzle for another. It is highly advantageous that this adjustment be made from the exterior, since the exhaust pipe and nozzle members are situated in a portion of the locomotive where the normal heat may equal or exceed 800° F.

We have illustrated a particularly advantageous structure wherein the web or side members C C¹ are formed integrally with the nozzles C² and C³. However if desired the same structure may be of two or more pieces.

The selective nozzle structure, mounted on the webs or segments C C¹, is trunnioned to the exterior of the exhaust pipe or stand member B¹, the bearing portions being thus out of the line of travel of the vapor or steam discharged. This is important, since otherwise the metal of the bearing surfaces would rapidly be affected. Owing to the high temperature, opposed bearing parts are subjected to unusually difficult wearing conditions.

We therefore provide the removable trunnion member C⁸. Opposed to it is the end of the shaft D, which may of course be axially moved inwardly to compensate for wear, or may be withdrawn, for example by removal of the plate member C¹¹.

In order to limit the movement of the duplex nozzle member we provide the stop lug B⁶ with its inclined faces B⁷ B⁸. Opposed to these faces are the lugs C²⁰ and C²¹ respectively, on the opposite edges of the webs C and C¹. Owing to the inclination of the opposed surfaces of the various stops the stops are self-cleaning.

Our selective nozzle arrangement efficiently

copes with draft variations. In practical use, the draft varies with the quality of fuel, a smaller or more highly inclined or tapered nozzle being advantageous to compensate for the use of poor fuel. The draft may also vary with different firemen, since some firemen run a deeper fire bed and need a sharper draft. Whatever be the cause of the variations, we provide an efficient, easily operated and externally controlled means for varying the draft by varying the velocity of discharge of the exhaust steam.

We claim:

1. The combination with a locomotive exhaust pipe of a multiple nozzle member pivoted thereto, a plurality of nozzles associated with said member, said member including web sections extending downwardly about the exhaust pipe and trunnioned to the exterior thereof.

2. The combination with a locomotive exhaust pipe of a multiple nozzle member exteriorly trunnioned thereto, and means for rotating said member to position the individual nozzles thereof selectively in operative relation with said exhaust pipe, and removable trunnion members therefor.

3. The combination with a locomotive exhaust pipe of a multiple nozzle member trunnioned upon said exhaust pipe, and means, operable from the exterior of the locomotive, for moving it to position selectively the individual nozzles of said multiple nozzle members in operative relation with said exhaust pipe, and stop means adapted to limit the excursion of said nozzle member to predetermined limits.

4. The combination with a locomotive exhaust pipe of a multiple nozzle member trunnioned thereupon, a plurality of nozzles associated with said member, means for rotating said member to position said nozzles selectively in operative relation with the exhaust pipe, and opposed fixed stop members on the multiple nozzle member and the exhaust pipe, adapted to limit the movement of said nozzle member at the extremities of its excursion, to align the individual nozzles with the exhaust pipe, the opposed surfaces of said stop members being inclined to the path of movement of the nozzle member.

5. The combination with an exhaust pipe for locomotives and the like of a removable nozzle therefor, a trunnion supporting the nozzle when out of working relation with the exhaust pipe, means interposed between the nozzle and the exhaust pipe for rigidly holding the nozzle in register with the end thereof independent of the trunnion.

6. The combination with an exhaust pipe for locomotives and the like of a removable nozzle therefor, a trunnion supporting the nozzle when out of working relation with the exhaust pipe, means interposed between the

nozzle and the exhaust pipe for rigidly holding the nozzle in register with the end thereof independent of the trunnion, said means comprising cam lugs associated with the exhaust pipe and the nozzle and so positioned as to come into engagement one with the other when the nozzle and exhaust pipe are in line and to force the nozzle axially against the

end of the exhaust pipe responsive to movement of the axis of the trunnion. ¹⁰

Signed at Chicago, in the county of Cook, and State of Illinois, this 27th day of September, 1926.

ROBERT R. BUSH.
CHARLES W. DAKE.
